Primary Examiner — Catherine Ho(74) **Attorney, Agent, or Firm** — Dinsmore & Shohl LLP**CLAIM**

The ornamental design for a geometrical column unit, as shown and described.

DESCRIPTION

FIG. 1 is a top front perspective view of a geometrical column unit showing my new design;

FIG. 2 is a front side elevational view thereof, the back side elevational view being a mirror image thereof;

FIG. 3 is a right side elevational view thereof, the left side elevational view being a mirror image thereof; and,

FIG. 4 is a top plan view thereof, the bottom plan view being a mirror image thereof.

The new, original, and ornamental design of a geometrical column unit is contemplated to be a repeatable single segment capable of being stacked at the top and/or bottom surfaces.
